Patented Dec. 13, 1921.

Hans Hansen INVENTOR
BY William Edwards Jr. ATTORNEY

UNITED STATES PATENT OFFICE.

HANS HANSEN, OF KANSAS CITY, MISSOURI.

WRINGER.

1,400,433.

Specification of Letters Patent. Patented Dec. 13, 1921.

Application filed May 19, 1921. Serial No. 470,896.

To all whom it may concern:

Be it known that I, HANS HANSEN, a citizen of the United States, residing at Kansas City, in the county of Jackson and State of Missouri, have invented certain new and useful Improvements in Wringers, of which the following is a description, referring to the drawings which accompany this specification.

10 The invention relates particularly to wringers of the type employed in laundry operations and refers to a simple and effective means for the application and quick release of the spring clamping mechanism 15 as further shown and described.

In the drawings, Figure 1 shows my improved wringer in operative combination with a washing machine and power driving mechanism. Fig. 2 shows a front view of 20 the wringer seen in Fig. 1 with the spring bar released. Fig. 3 is a top view of my wringer mechanism. Fig. 4 is a top view of 25 the top housing member of the device. Fig. 5 is an enlarged sectional detail of the top housing member and the operative elements in combination therewith.

Similar numerals of reference indicate corresponding parts throughout all the figures of the drawings.

30 Referring to the drawings, 10 represents a washing machine of the dasher type. At 11 a motor is indicated driving transmission mechanism contained and operable within a case 12. This mechanism operates the rack 35 bar 13 for washing machine operation and also drives the bottom roll 14 of the wringer. The top roll 15 and the bottom roll 14 are mounted in bearings contained within the frame housings 16, 17 of the wringer; the 40 bottom roll maintains a fixed relationship, while through vertical adjustable movements of the bearings the upper roll may be set to a close working relationship with the bottom roll as seen in Fig. 1 and in which 45 position the wet clothes are passed between the rolls for wringing purposes. Frequently the space between the rolls as in Fig. 1 is not sufficient to permit passage of the clothes, which occasionally become bunched, or possibly 50 the operator's fingers get caught between the rolls; then, it is very essential that a quick release may be permitted such as will allow the upper roll to move upwardly away from the bottom roll to the position 55 illustrated in Fig. 2.

The top brace 18 connecting the housings 16, 17 is provided with a vertical slot 19

which is arranged at one side of and connected with the central bearing 20 within which the bushing 21 is vertically mounted. 60 The bushing 21 has a side catch 22 extending into the slot 19. A screw 23 fitted with a hand wheel 24 is adjustably screwed down in the threaded upper portion of the bushing 21 to a contact with the pin 25 slidably 65 mounted upwardly within the bore of the bushing 21. The base head 26 of the pin 25 envelops the central portion of the spring bar 27 which bears at its outer ends against the bearings of the upper roll 15. 70

Pivottally mounted at 28 within the slot 19 is a dog 29 which in Fig. 5, corresponding to the position of the parts in Fig. 1, engages with the catch 22 to maintain the bushing in a fixed relationship with the rigid cross 75 brace 18. The wheel 24 is then turned down to exert a desired tension on the spring bar 27 through the pin 25; the bar 27 then sets the top roll 15 in operative position with respect to the bottom roll 14. 80

A hand lever 30 is pivotally mounted at 31 within the slot 19 with the handle 32 upwardly arranged above the brace 18 and an inner tooth 33 of the lever 30 engaged between the teeth 34, 35 of the dog 29. A 85 spring 36 is arranged between the dog 29 and lever 30 to normally force the dog 29 and lever 30 to the position seen in Fig. 5.

Should a sudden clogging occur between the top and bottom rolls, a downward blow 90 is struck on the handle 32 which forces the tooth 33 to raise the dog tooth 34 to the dotted position 34*, Fig. 5, which pivotally withdraws the dog 29 from the catch 22 to the dotted position 29*; then the spring tension 95 in the bar 27 automatically forces the pin to raise the bushing 21 and screw 23 to the position seen in Fig. 2 where the head 37 of the bushing 21 contacts the under side of the member 18. This permits the top 100 roll to move upwardly a considerable distance from the bottom roll so that the clogging material may be removed from between the rolls. 105

To again place the parts in the operative position seen in Figs. 1 and 5, the wheel 24 in Fig. 2 would be turned backward a turn or two, then a downward blow struck upon the wheel 24 which would drive the parts downwardly until the catch 22 was again 110 engaged by the dog 29 as actuated by the spring 36, then the wheel 24 is screwed down a turn or two to again create the desired spring tension on the bar 27.

By means of my invention a quicker and more positive action is obtained than is customary in common practice.

Such modifications may be employed as lie within the scope of the appended claims. Having fully described my invention what I now claim as new and desire to secure by Letters Patent is:

1. In a wringer, paired side housings, a top brace member connecting said housings, said brace member having a vertical shaft bearing centrally arranged therein and a vertical slot at one side of said bearing and connected therewith; a bushing slidably mounted within said shaft bearing, a flanged head at the base of said bushing and below said top brace member, a side catch on said bushing arranged within said vertical slot; a pair of wringer rolls arranged one above the other within said housings, the upper roll being vertically adjustable, a spring bar above and spanning the bearings of said upper roll, a pin rigid with said spring bar at the center thereof and upwardly sleeved within said bushing, a dog pivotally mounted within said vertical slot and in locking engagement with the side catch on said bushing; and lever means pivotally mounted within said vertical slot and in operative engagement with said dog.

2. In a wringer, paired side housings, a top brace member connecting said housings, said brace member having a vertical shaft bearing centrally arranged therein and a vertical slot at one side of said bearing and connected therewith; a bushing slidably mounted within said shaft bearing, a flanged head at the base of said bushing and below the top brace member; a side catch on said bushing arranged within said vertical slot; a pair of wringer rolls arranged one above the other within said side housings, the upper roll being vertically adjustable, a spring bar above and spanning the bearings of said upper roll, a pin rigid with said spring bar at the center thereof and upwardly sleeved within said bushing, a dog pivotally mounted within said vertical slot and in locking engagement with the side catch on said bushing; and lever means pivotally mounted within said vertical slot and in operative engagement with said dog; the upper bore of said bushing being threaded and a screw adjustably screwed therein to exert pressure upon said pin and occasion a downward spring thrust action of said spring bar upon said upper roller substantially as specified.

3. In a wringer, paired side housings, a top brace member connecting said housings, said base member having a vertical shaft bearing centrally arranged therein and a vertical slot at one side of said bearing and connected therewith; a bushing slidably

mounted within said shaft bearing, a flanged head at the base of said bushing and below the top brace member, a side catch on said bushing arranged within said vertical slot; a pair of wringer rolls arranged one above the other in bearings contained in said housings, the upper roll being vertically adjustable, a spring bar above and spanning the bearings of said upper roll, a pin rigid with said spring bar at the center thereof and upwardly sleeved within said bushing, a dog pivotally mounted within said vertical slot and in locking engagement with the side catch of said bushing at one end and having projecting teeth at the other end; the upper bore of said bushing being threaded and a screw adjustably screwed therein to exert pressure upon said pin and occasion a downward spring thrust action of said spring bar upon said upper roller and a hand lever pivotally mounted within said vertical slot, a tooth thereon in engagement between teeth of said dog.

4. In a wringer, paired side housings, a top brace member connecting said housings, said brace member having a vertical shaft bearing centrally arranged therein and a vertical slot at one side of said bearing and connected therewith; a bushing slidably mounted within said shaft bearing, a side catch on said bushing arranged within said vertical slot; a pair of wringer rolls arranged one above the other in bearings in said side housings, the upper roll being vertically adjustable, a spring bar above and spanning the bearings of said upper roll; a pin rigid with said spring bar at the center thereof and upwardly sleeved within said bushing, a dog pivotally mounted within said vertical slot and in locking engagement with the side catch of said bushing at one end and having projecting teeth at the other end; the upper bore of said bushing being threaded and a screw adjustably screwed therein to exert pressure upon said pin and occasion a downward spring thrust action of said spring bar upon said upper roller during the locking engagement of said dog and side catch; a hand lever pivotally mounted within said vertical slot, a tooth thereon in engagement between the teeth of said dog, a spring arranged intermediate said lever and dog normally serving to preserve the said locking engagement of said dog and catch; said lever under downward handle movement operating to release said dog from said catch against such spring pressure and effect spring bar pressure release from said upper roll, all for the purposes substantially as specified.

HANS HANSEN.
